UNITED STATES PATENT OFFICE.

FLORENCE DE RANGIS, OF HAVERHILL, MASSACHUSETTS, ASSIGNOR OF
ONE-FOURTH TO EDWARD H. BARRY, OF HAVERHILL, MASSACHUSETTS.

REVERSIBLE STOVE.

SPECIFICATION forming part of Letters Patent No. 785,063, dated March 14, 1905.

Application filed May 5, 1904. Serial No. 206,500.

To all whom it may concern:

Be it known that I, FLORENCE DE RANGIS, of Haverhill, county of Essex, State of Massachusetts, have invented an Improvement in Reversible Stoves, of which the following description, in connection with the accompanying drawings, is a specification, like characters on the drawings representing like parts.

This invention relates to certain improvements in that class of stoves known as "cooking-stoves" or "ranges." Stoves of this character are made either right-handed or left-handed—that is, with the fire-box or hearth at the right or at the left of the front side, as may be desired. To fulfil all requirements, it is necessary for dealers to keep both kinds in stock, and it often happens that when a person changes his abode he is obliged to exchange his range, which has the fire-box at the right, for one which has its fire-box at the left.

The object of my invention is to provide a stove of the above-named character which is so constructed that the parts may be readily interchanged and connected together to form a stove having its fire-box either at the right or at the left. I accomplish this object by the means shown in the accompanying drawings, in which—

Figure 1 is a side elevation of a stove made according to my invention with the parts so arranged that its fire-box end is at the left. Fig. 2 is a plan view thereof. Fig. 3 is an enlarged detail view on the line 3 3 of Fig. 1. Fig. 4 is a vertical cross-sectional view on the line 4 4 of Fig. 2. Fig. 5 is a front view of the oven with the fire-box and closure sections removed. Fig. 6 is a plan view of the bed-plate. Fig. 7 is a sectional view on the line 7 7 of Fig. 4. Fig. 8 is a sectional view on the line 8 8 of Fig. 4. Fig. 9 is a sectional view on the line 9 9 of Fig. 4. Fig. 10 is a side elevation, partly in section, of the stove with the parts arranged so that its fire-box is at the right. Fig. 11 is a view of one end of the oven with the closure-section removed.

As shown in the drawings, a flat bed-plate *a* of rectangular form is mounted upon a frame *a'*, which is supported by a series of legs *b* at

each corner in the usual manner. The bed-plate *a* is provided with a flange *a*², which extends about the entire edge thereof, and with a series of lugs *a*³, which are arranged closely adjacent the rib *a*⁷ in lines parallel to said ribs, so as to provide a groove therebetween. 50 The oven portion *c* is provided with the usual oven-chamber and with cover-supporting top plates *c*², which extend longitudinally thereof. The oven is also provided with depending flanges *c*³, which extend from the front to 55 the rear end of the oven at each side thereof, said flanges being adapted to seat between the rib *a*² and the lugs *a*³, as shown in Fig. 10, so as to support the bottom of the oven at a suitable distance above the upper surface of the 60 bed-plate *a* to provide the usual bottom circulating-chamber and to hold the oven in place. This construction permits the oven portion to be moved to various positions on the bed-plate and at the same time to maintain a tight 65 connection with the bed-plate at each side thereof.

The fire-box section of the stove comprises the hearth *d* and ash-pit tray *d'*, the front end wall *e*, the two side walls *f f'*, and the top 70 plate *g*.

Each corner of the oven is provided with a pair of longitudinally-extending flanges *a*⁴, said flanges each being inwardly offset to provide a seat and an abutting shoulder for the 80 inner side portions and the edges of the side walls *f f'*. The lower edges of said side walls *f f'* are adapted to seat in the grooves between the flanges *a*² and lugs *a*³, and the front edge portions thereof are adapted to overlap rearwardly-extending flanges *e*' on the front wall *e*. (See Fig. 7.) Said front and side walls are connected to each other and also to the top-plate *g*, which rests on horizontal flanges which project from the upper edges of said 85 walls. The rearwardly-extending portions *g*' of plate *g* overlap and are removably connected to offset ears *c*⁵, formed on the ends of the lid-rests *c*². (See Fig. 4.) The front wall *e* is provided with a rectangular opening, as 90 shown in Fig. 9, the upper portion of which is adapted to be closed by the usual door *d*⁴, hinged on the hearth *d*. The tray *d'* fits into

the lower portion of said rectangular opening, which is correspondingly shaped to receive it. The rearwardly-extending horizontal portions d^3 of the hearth are longitudinally slotted to receive the walls $f^3 f'$ and also the portions of the wall e between the ends of slots therein which lead from said opening to receive the hearth portions d^3 and the outer edges thereof. The end of the tray d' fits closely beneath a rib c^6 , formed on the end of the oven wall, and a rib i' , formed on the front side of a door-plate i , which is adapted to close either end of the chamber between the bottom of the oven and the bed-plate, a seat to receive said door being formed therefor at each end of the oven, as shown in Figs. 4, 7, 8, 10, and 11. The front end of the tray portion of the hearth and the upper portion of the rectangular portion of the wall e are provided with a seat for the door d^4 . (See Figs. 4 and 7.) The hearth-piece and ash-pan tray are firmly bolted to the side walls $f^3 f'$, as illustrated in Fig. 7.

A closure-section k is provided, the lower edge of which is adapted to seat in the grooves between the lugs a^3 and the flange a^2 , and which is provided with forwardly-extending flanges k' , which overlap the offset flanges c^4 on the adjacent corners of the oven, as shown in Figs. 3 and 7. The top plate k^2 of section k overlaps the rear ends of top plates c^2 . Said overlapping flanges are bolted together and said closure-section may be otherwise securely clamped to the oven by any suitable or convenient means, as shown in Figs. 2, 3, 4, and 7.

A smoke-pipe p is secured to the rear side of the oven and passes through an opening p' , provided therefor in the rear flange c^3 , so that said pipe is always in open communication with the chamber between the oven and bed-plate. An opening p^2 is also provided in the side of the oven, which extends above its top to support the cover-plates c^2 to afford communication between the fire-box and the pipe p , said opening being adapted to be closed by the usual damper. Grooves $c^7 c^8$ are formed by parallel ribs on the bottom of the oven at each side of the smoke-pipe opening p' . Grooves a^5 and a^6 are also formed in the bed-plate a , so that when the oven is in the left-hand position, as shown in Fig. 4, the groove a^5 will register with the seat formed for closing-plate i at the left-hand end of the oven, and the groove c^8 will be directly over the groove a^6 , and when the oven is in the right-hand position of Fig. 10 the groove a^6 will register with the plate-seat formed for plate i at the right-hand end of the oven and the groove c^7 will be directly over the groove a^5 . When the stove is set up with the fire-box section at the left, as in Fig. 4, the plate i will be arranged to close the left-hand end of the chamber below the oven and a baffle-plate m will be inserted in the grooves $c^8 a^6$, with its rear end against the rear flange c^3 and extending about two-thirds of the dis-

tance across the bed, (see Fig. 6,) said plate m subserving its usual function. When in the right-hand position, plate i will be seated in groove a^6 and plate m will be seated in grooves $a^5 c^7$. 70

The front and rear ends of the oven are provided with grate-rack-supporting lugs c^9 , and the front wall e is provided with similar lugs on which the grate-rack n of the grate n' rests. The fire-box above the grate is lined with the usual bricks q . 75

The removable lids and lid-frames, which are supported by the plates c^2, g , and k^2 , preferably comprise a central rectangular lid-frame s and four square end frames s' . The frame s has two lid-apertures and the others have a single lid-aperture. 80

The usual doors $t t' t^2$ are provided and the parts comprising the hinge-lugs and catches of the oven-door t are formed on strips t^3, t^4, t^5 and t^6 , which may be interchanged when it is desired to have the door hinged from one end instead of the other. 85

So far as the practical working of the stove is concerned it is no different from any ordinary stove of this class. 90

If it is desired to change the stove so that its fire-box will be at right, as shown in Fig. 7, instead of at the left, as shown in Fig. 1, it is simply necessary to disconnect and remove the fire-box or hearth section from the adjacent end of the oven and the closure end section from the other end of the oven, then move the oven toward the left on the bed-plate to a corresponding position with relation to the opposite end of the bed-plate. The fire-box section is then connected to the right-hand end of the oven and the closure-section is connected to the left-hand end in the manner before described, the plates i and m being changed to the positions of Fig. 10, the grate being reversed and the catch-lugs and hinges of the oven-door being interchanged, as will be obvious without further explanation. 100

Having thus described my invention, what I claim as new, and desire to secure by Letters Patent, is— 110

1. In a stove of the character described, a bed, an oven mounted thereon, and interchangeable fire-box and closure sections arranged at opposite sides of the oven, substantially as described. 115

2. In a stove of the character described, a bed, an oven adjustably mounted thereon, and interchangeable fire-box and closure sections arranged at opposite sides of the oven, substantially as described. 120

3. In a stove of the character described, a bed-plate having a longitudinally-extending edge rib at each side thereof, an oven adjustably mounted on said bed between said ribs, and interchangeable fire-box and closure sections arranged at opposite sides of said oven and bed-plate, substantially as described. 125

4. In a stove of the character described, a 130

bed-plate, an oven adjustably mounted thereon, longitudinally-extending supporting-flanges for said oven at each side of said bed-plate, to provide a flue-chamber between the bottom of the oven and said bed-plate, and interchangeable fire-box and closure sections at opposite sides of the oven, substantially as described.

5. In a stove of the character described, a bed-plate, an oven adjustably mounted thereon, longitudinally-extending supporting-flanges for said oven at each side of said bed-plate to provide a flue-chamber between the bottom of the oven and said bed-plate, a door-plate for closing either the front or rear end of said chamber, and interchangeable fire-box and closure sections removably connected to opposite sides of the oven, said closure-sections providing a passage connecting said flue-chamber with the space above the oven, substantially as described.

10. In a stove of the character described, a bed, an oven, longitudinally-extending supports between said bed and oven providing a circulating-chamber therebetween, a plate adapted to close either end of said chamber, and interchangeable fire-box and closure sections connected to opposite sides of the oven, substantially as described.

15. In a stove of the character described, a bed, an oven adjustably mounted thereon, and interchangeable fire-box and closure sections connected to opposite sides of the oven, said

fire-box section comprising a front wall having a front opening, a hearth, and an ash-pit tray connected to said hearth and removably fitted in the lower end of said opening, substantially as described.

20. In a stove of the character described, a bed-plate, an oven adjustably mounted thereon, longitudinally-extending supporting-flanges for said oven at each side of said bed-plate to provide a flue-chamber between the bottom of the oven and said bed-plate, said rear supporting-flange having a flue-passage therethrough leading into said chamber, a baffle-plate, means for removably supporting the same transversely of said chamber at either side of the entrance to said flue-passage, and interchangeable fire-box and closure sections connected to opposite sides of the oven, substantially as described.

25. In a stove of the character described, a bed, an oven adjustably mounted thereon, and interchangeable fire-box and closure sections connected to opposite sides of the oven, said sections and oven having overlapping connecting-flanges, substantially as described.

In testimony whereof I have signed my name to this specification in the presence of two subscribing witnesses.

FLORENCE DE RANGIS.
